UNITED STATES PATENT OFFICE.

SAMUEL B. ZIMMER, OF LOS ANGELES, CALIFORNIA.

CONTROL HINGE.

Application filed March 9, 1927. Serial No. 173,878.

This invention relates to control hinges, and more particularly to adjusters for swinging casements, transoms and the like, and it is an object of this invention to provide a device which may be attached to the jamb adjacent the swinging casement and which is attachable to the casement itself and permits of swinging motion of the same. The rattling and banging of swinging casements such as shutters or blinds or French windows during a wind storm is familiar to everyone, and it is an object of my invention to remedy this by providing a casement adjuster that will permit a casement to be left completely open without danger of the residents being disturbed by such noises.

Another object of this invention is to provide a combination device of the character indicated which can be readily made of sheet-metal stampings and which at the same time is light and strong.

A still further object is to provide a novel construction of control hinge, whereby in the act of swinging the casement, a powerful leverage is exerted on the same in the direction of the opening or closing thereof, to readily start the same from the jamb as the pressure exerted is applied thereto manually.

A still further object of this invention is to provide a device which is strong and durable in construction, operates efficiently and is well adapted to perform the services required of the same.

With these and many other objects in view, which will more readily appear as the nature of the invention is better understood, the same consists in the novel construction, combination, and arrangement of parts, which will hereinafter be more fully described, illustrated and claimed.

The essential features of the invention involved in the carrying out of the objects indicated are susceptible to modification; but a preferred embodiment of the invention is shown in the accompanying drawings, in which—

Figure 1 is a top plan view showing my device applied to the jamb of a swinging casement such as a French window or the like.

Fig. 2 is a side elevation of the illustration shown in Figure 1, and

Fig. 3 is a detailed sectional view of my improved construction showing the casement in open position.

Like reference characters designate cor-

responding parts throughout the several figures of the drawings, and in my invention, while the various elements thereof may be constructed in any suitable manner and of any suitable material, yet it is preferable to form the hinge of sheet-metal stampings on account of the cheapness, lightness and strength of the latter; but irrespective of these details in manufacturing, the essential features of the invention are always preserved.

The device involves in its general organization, a hinge having leaves or sections 1 and 2. The section 1 being applied to the jamb 3 of a casement in the manner indicated in Figure 1, and the section 2 being applied to the casement itself as shown in this same figure. The section 1 is preferably in the form of a substantially Z-shaped stamping having a portion 4 attached to the jamb, a central portion 5 through which there is an aperture 6 and a portion 7, the outer end of which is curved to form a journal for a pintle 8. The section 2 of the hinge is preferably in the form of a slightly bent metal stamping having a portion 9 attached to the casement and a portion 10, the outer end of which is rounded in the manner similar to which the portion 7 of the section 1 is rounded, also to receive the pintle 8. Cut-out portions 13 and 14 are formed in each of the hinge sections to provide a space wherein a pair of beveled gears may operate and which will be described at a point 90 later in this specification. Second cut-out portions 15 and 16 are formed on adjacent edges of each of the hinge sections respectively, so that the sections may be complementary and cooperate upon the pintle to 95 form a hinge having perfect alignment with respect to the pintle 8. The various cut-out portions in the hinge are so arranged that each section may be reversed upon the other to permit opposite swinging of a casement if 100 the same is necessary. Loosely mounted on the pintle 8 which acts as a shaft therefor, is a beveled gear 20 having a pair of lugs 21 and 22, and a supporting shank 27. These lugs 21 and 22 are spaced a slight 105 distance apart and receive the upper edge of the cut-out portion 13 in the section 1. Extending through the jamb 3 of the casement is a shaft 23 having on the outer end thereof a bearing 24. The outer end of this shaft 110 is squared as at 25 to receive a square, apertured crank-handle 26. A coil-spring 30 is

disposed around this squared portion and a friction disc 29 abuts against the coil-spring and the bearing 24 for a purpose to be described hereinafter. The inner end of the shaft 23 has thereon, a beveled gear 28 having teeth which engage the teeth of the beveled gear 20 so that rotation of the gear 28 will cause rotation of the gear 20 and consequently of the casement itself. From the foregoing it is thought that the construction of the herein described control hinge will be apparent without further description of the parts, and the operation of this device will now be described.

The device is applied to the operative parts of the casement and jamb as shown in Figure 1. When it is desired to open the casement or partially open the same, the handle 26 is manually rotated and motion is imparted to the beveled gear 28 through the shaft 23. This motion of the beveled gear 28 causes motion of the beveled gear 20, and the lugs 21 carry the hinge in a rotary direction upon the pintle 8 so that the casement will be swung open. If the casement should be swung from its opposing edge in an opposing direction, it is merely necessary to remove the pintle 8, which may easily be done by removing one of the small knobs on the pintle, and the hinge may be reversed by virtue of its construction, and the beveled gear 20 may also be reversed upon the pintle so that it will occupy a position below the beveled gear 28. The device will then be set so that it may be applied to a casement that swings in the opposite direction from that shown.

From the foregoing it is thought that the construction, use and many advantages of the herein-described control hinge will be readily apparent without further reference, and it will also be understood that changes in the form, proportion, and minor details of construction may be resorted to without departing from the spirit of the invention or sacrificing any of the advantages thereof. For example, my device may readily be ap-

plied to swinging transoms by providing a small pulley in place of the handle 26, and permitting a belt or the like to run down the side of the jamb or within the jamb itself, and providing a suitable handle at a convenient point on the jamb whereby motion may be imparted through the said belt to the pulley thus serving to operate the parts.

Having thus described the invention, what is claimed and desired to be secured by Letters Patents, is:

1. A hinge for swinging casements and the like comprising a pair of pivoted hinge leaves, one of which is attachable to the casement and the other to the jamb thereof, said leaves being provided with adjacent cut out portions, a gear mounted for rotation within said cut out portion, said gear having lugs arranged to engage opposite sides of the casement leaf, a second gear meshing with said first mentioned gear, and manually operated means for rotating said second gear to rotate said first mentioned gear to cause the casement leaf to swing upon the jamb leaf.

2. A hinge for swinging casements and the like comprising a pair of hinged leaves, a pintle pivoting them together, one of said leaves being substantially Z-shaped and attachable to perpendicular planes upon the jamb, the other section being slightly bent and attachable to the inner edge of the casement whereby the outer ends of said leaves may close upon each other, cut out portions in said leaves on either side of said pintle, a gear mounted on said pintle and within said cut out portions, said gear being provided with upstanding lugs adapted to engage opposite sides of the casement leaf, a second gear meshing with the first gear, a shaft fast to said second gear and passing through said jamb, manually operated means for rotating said shaft, and frictional means retarding the rotation of said shaft.

In testimony whereof I have signed my name to this specification.

SAMUEL B. ZIMMER.
